UNITED STATES PATENT OFFICE.

RUDOLPH GRAFF, OF MARTINS FERRY, OHIO, ASSIGNOR TO MICHAEL RIGO, STEVEN RIGO, STEVEN BALAZS, ANDREW BALAZS, JOHN BIRO, AND RUDOLPH GRAFF, PARTNERS TRADING AS FIRST HUNGARIAN INVENTORS COMPANY, OF MARTINS FERRY, OHIO.

ICE-CREEPER.

1,044,776.

Specification of Letters Patent. Patented Nov. 19, 1912.

Application filed July 2, 1912. Serial No. 707,205.

To all whom it may concern:

Be it known that I, RUDOLPH GRAFF, a subject of the King of Hungary, and resident of Martins Ferry, county of Belmont, 5 and State of Ohio, have invented certain new and useful Improvements in Ice-Creepers, of which the following is a specification.

This invention relates to certain new and 10 useful improvements in ice creepers, and it has for its primary object the provision of a device of this character having novel form, which is instantly adjustable to any of the various shapes and sizes of shoe 15 soles.

A further object of the invention is to provide an ice creeper which is of simple, durable and economical construction and which possesses a minimum number of parts.

With these and other objects in view, the 20 invention resides in the features of construction, arrangement of parts, and combinations of elements which will herein-after be fully described, reference being had 25 to the accompanying drawings, forming a part of this specification, in which—

Figure 1 is a perspective view of the invention applied to a shoe sole; Fig. 2 is a top plan view, the casing being shown in 30 section; Fig. 3 is a longitudinal section on the line 3—3, Fig. 2; Fig. 4 is a cross section on the line 4—4, Fig. 2; and Fig. 5 is a detail fragmentary view, illustrating one of the spikes or studs.

Referring to said drawings, in which like 35 designating characters distinguish like parts throughout the several views—1 indicates a casing of substantially U-shape in cross section which has the free edges of its longitudinal sides 2 bent over inwardly as depicted at 3 in Fig. 4, so as to engage the outer face of the outer bar 4 of a pair of bars 4 and 5 which are disposed in superposed relation within the embrace of said 40 casing. Each of the bars 4 and 5 is formed with an elongated slot 6 therein through which passes a bolt 8 having a head 9 in engagement with the outer face of the bar 4 at opposite sides of the slot 6 provided 45 in the latter, and a nut 10 is threaded upon the end of said bolt to bind upon the bottom of casing 1 for maintaining said bars in adjusted relation.

The bolt 8 has a stationary relationship to

the casing, being seated in a perforation 55 provided therefor in the bottom or body portion of the casing. The adjacent or contacting faces of the bars 4 and 5 are preferably milled or otherwise roughened, as illustrated in Fig. 3, means being thus provided whereby chance movement of the bars from adjusted position is effectually guarded against.

A pair of oppositely disposed shoe clamps have pivotal connection with the body portion of the device hereinbefore described, each clamp comprising a curved plate 11 having an integral lateral extension 13 located at a point substantially midway between its ends. As shown at the right-hand 65 side of Fig. 3, the extension of one of said clamps has its end disposed between the adjacent ends of the outer bar 4 and the body of the casing 1 and is pivoted upon a rivet-like pivot-pin 14 which has its opposite ends 70 held in said ends of the bar 4 and casing 1, said pivot-pin also serving to maintain said bar and casing in fixed relation. The extension of the opposite clamp lies, as shown at the left-hand side of Fig. 3, upon the 75 adjacent end of the inner bar 5 and is pivoted upon a rivet-like pivot-pin 15 which is mounted in a stationary position in said end of said inner bar 5 so as to admit of longitudinal movement of said bar and 80 the casing with respect to each other. Each of the plates 11 stands at substantially a right angle to the position of the base and has formed thereon at points adjacent to the opposite ends thereof shoe-sole-engaging 85 hooks, each consisting of an upright member 12 adapted to lie close against the edge of a shoe sole and terminating in an in-turned lip 12^a adapted to overlie the sole, as is clearly depicted in Fig. 1. The upper 90 right members 12 of said hooks are disposed in any preferred laterally facing position to adapt said hooks for lying closely in engagement with the shoe sole at points more or less widely separated. As is obvious, the pivotal mounting of the clamps 95 adapts the latter for movement to any position requisite to conform to the curvature of shoe soles of widely varying contours. Each of the clamps has pointed studs or 100 spikes 17 secured thereto in appropriate 105 positions, said spikes being attached by providing same with threaded shanks 16 for

engagement in threaded perforations in the plate 11 or by rigidly connecting the parts in any other approved manner.

In practice, the nut 10 is loosened and the bars 4 and 5 are adjusted longitudinally with respect to each other to cause the clamps to approach or move away from each other, as required. Having been adjusted to effect clamping engagement between the hooks and the shoe sole, the nut is tightened to draw the bars 4 and 5 and the casing 1 into binding relation for effectively locking all of the parts against movement.

From the foregoing it will be seen that the parts are of simple and economical construction and that to place said parts in condition for immediate attachment, removal, or adjustment, requires the manipulation of but one part, namely, the nut 10.

Having thus described my invention, what I claim as new, and desire to secure by Letters Patent, is—

1. An ice creeper comprising a casing of substantially U-shape in cross-section, a pair of longitudinally movable bars disposed in superposed relation within the embrace of said casing and having non-adjacent ends projecting outward from the opposite ends of said casing, said bars having registering longitudinal slots therein in which is received the body of a headed bolt mounted in the casing, sole clamps connected to the projecting ends of said bars to be adjustable with respect to each other with movement of said bars, spikes carried by said clamps, and a nut on the outer end of the bolt for binding against the casing.

2. An ice creeper comprising a casing of substantially U-shape in cross-section, a pair of longitudinally movable bars disposed in superposed relation within the embrace of said casing and having non-adjacent ends projecting outward from the opposite ends of said casing, said bars having registering longitudinal slots therein in which is received the body of a headed bolt mounted in the casing, sole clamps having pivotal connection with the projecting ends of said bars, and means acting on said bolt for binding said bars in adjusted position.

3. An ice creeper comprising a stationary member, a pair of longitudinally movable bars mounted in superposed relation upon said member, each of said bars having an end projected outward beyond the adjacent

end of the other, a rivet holding the projecting end of the outer bar in fixed relation to said member, a sole clamp having a portion pivoted on said rivet between the projecting end of said outer bar and said member, a sole clamp pivoted to the projecting end of the opposite bar, spikes carried by said clamps, and means for securing said bars in adjusted relation.

4. An ice creeper comprising a stationary member, a pair of longitudinally movable bars mounted in superposed relation upon said member, each of said bars having an end projected outward beyond the adjacent end of the other, a rivet holding the projecting end of the outer bar in fixed relation to said member, a sole clamp having a portion pivoted on said rivet between the projecting end of said outer bar and said member, a sole clamp pivoted to the projecting end of the opposite bar, said bars having longitudinal registering slots therein, a bolt mounted in a stationary position in said stationary member and projected outward through said slots, adjustable means acting on said bolt for binding said bars in adjusted position, and spikes carried by said clamps.

5. In combination with a casing, a spiked clamp pivotally secured to one end of the casing, a bar engaging one end of the clamp and being spaced from the casing, a second bar arranged in the space between the casing and the first named bar and having a longitudinal slot, a spiked clamp pivoted to the outer end of the second named bar, and a nut and bolt connection passing through the casing, the first named bar, and the slot of the second bar to secure the latter in adjusted position.

6. An ice creeper including a stationary member having a bolt therein and a clamp pivoted to one end thereof, a bar having a clamp pivoted to one end thereof and having its other end slotted, said bolt passing through the slot in the bar, and a nut on the bolt to bind the bar to the stationary member.

In testimony whereof I affix my signature in presence of two subscribing witnesses.

RUDOLPH GRAFF.
